(57) **CLAIM**

The ornamental design for a compression undergarment, as shown and described.

DESCRIPTION

FIG. 1 is a perspective view of a first embodiment of a compression undergarment.

FIG. 2 is a front view of a first embodiment of a compression undergarment.

FIG. 3 is a back view of a first embodiment of a compression undergarment.

FIG. 4 is a first side view of a first embodiment of a compression undergarment, the second opposing side being a mirror image thereof.

FIG. 5 is a top view of a first embodiment of a compression undergarment.

FIG. 6 is a perspective view of a second embodiment of a compression undergarment.

FIG. 7 is a front view of a second embodiment of a compression undergarment.

FIG. 8 is a back view of a second embodiment of a compression undergarment.

FIG. 9 is a first side view of a second embodiment of a compression undergarment, the second opposing side being a mirror image thereof; and,

FIG. 10 is a top view of a second embodiment of a compression undergarment.

The broken lines in the Figures do not form a part of the claimed design.
